Primary Examiner — Catheri Oliver-Garcia*(74) Attorney, Agent, or Firm* — Sheridan Ross P.C.(57) **CLAIM**

The ornamental design for a fish hook with a curved point, as shown and described.

DESCRIPTION

FIG. 1 is a front perspective view of a fish hook with a curved point;

FIG. 2 is a left side elevation view of the design of FIG. 1;

FIG. 3 is a right side elevation view of the design of FIG. 1;

FIG. 4 is a rear elevation view of the design of FIG. 1;

FIG. 5 is a front elevation view of the design of FIG. 1;

FIG. 6 is a top plan view of the design of FIG. 1; and,

FIG. 7 is a bottom plan view of the design of FIG. 1.

The broken lines in the drawings are provided for the purpose of illustrating environment and form no part of the claimed design.
